UNITED STATES PATENT OFFICE.

WILLIAM M. SPILMAN, OF McLAIN, MISSISSIPPI, ASSIGNOR OF ONE-HALF TO ROBERT H. COLEMAN, OF McLAIN, MISSISSIPPI.

COMBINATION GARMENT.

Application filed November 1, 1920. Serial No. 421,092.

To all whom it may concern:

Be it known that I, WILLIAM M. SPILMAN, a citizen of the United States, residing at McLain, in the county of Green and State 5 of Mississippi, have invented certain new and useful Improvements in Combination Garments, of which the following is a specification.

This invention relates to wearing apparel, 10 and the primary object of the invention is to provide a combination coat and shirt, which is so constructed that the weight of the improved combined garment will not be much more than the weight of an ordinary 15 shirt or coat, so that a person will be able to wear a coat during the warm weather with comfort and appear fully dressed for evening functions or other affairs where ladies are present.

Another object of the invention is to provide a shirt attachment for coats which are made of light material, such as cool cloth, duck, palm beach, pongee or the like, which require frequent laundering, the shirt being 20 permanently attached to the coat so that the parts of the garment may be laundered at the same time as a complete unit.

A further object of the invention is to provide a shirt coat, which will present a neat and dressy appearance to the eye so as to please the aesthetic taste, the shirt portion being constructed and arranged in such a manner in relation to the coat portion, that the device will give the same benefit to 30 the wearer without any annoyance as if an ordinary shirt was worn, without the additional weight thereof.

With these and other objects in view, the invention consists in the novel construction, 40 arrangement and formation of parts as will be hereinafter more specifically described, claimed and illustrated in the accompanying drawing, forming a part of this specification, in which drawings:

Figure 1 is an elevation looking into the garment, the garment being cut at the shoulder and spread open, so as to clearly show the construction thereof.

Figure 2 is a vertical transverse section 50 through the improved garment.

Figure 3 is an enlarged vertical section taken on the line 3—3 of Figure 2 and illustrating the guide for the support for the trousers.

Referring to the drawings in detail, 55 wherein similar reference characters designate corresponding parts throughout the several views, the letter A indicates the improved combined garment, which includes the coat portion B, and the shirt portion C. 60

The coat portion B is formed in the usual or any preferred manner and in accordance with any preferred style and can be made of any material, although a light weight material, such as pongee, palm beach, cool cloth or the like is preferred, as these materials have to be more or less frequently laundered.

The coat portion B includes the side portions 5 and 6 and the back portion 7. 70

The shirt portion C can be made out of any desired shirting material, such as silk, madras or the like, and includes the front portion 10, the rear portion 11, and the neck portion and shoulder portion 12. 75

The front portion 10 includes the two sections 13 and 14, the forward edges of which are adapted to overlap as in the usual shirt construction, and are connected in the usual manner by buttons 15. Each of these sections includes the upper bosom portion 16 and the lower skirt portion 17. The rear side edges of the bosom or chest portions are secured by a line of stitching 18 to the inner surface of the coat B directly in front of 85 the armholes 19. The skirt portion 17 of the sections 13 and 14 extend slightly rearwardly of the bosom or chest portion 16 thereof so that a full skirt portion 17 will 90 be formed.

The rear skirt or tail portion 11 is of a sufficient length so as to extend above the upper edge of the trousers, which are designated by the letter D in the drawings. This upper edge of the skirt is secured by means 95 of a line of stitching 20 to the inner surface of the coat. The forward upper edges of the tail or rear skirt 11 are arranged in abutting relation to the rear edges of the skirt portion 17 of the sections 13 and 14. 100

The neck portion 12 is preferably formed integral with the upper ends of the sections 13 and 14 of the front portion 10 of the shirt member C and this neck portion 12 includes the collar band 22 and the shoulder engaging portion 23. The inner edge of the shoulder engaging portion is connected by means of a row of stitching 24 with the

inner surface of the coat at the shoulder portion thereof. The collar band 22 as shown has a collar 25 detachably connected thereto but it is to be understood that the 5 collar may be permanently attached to the collar band if so desired.

By this construction, it can be seen that the entire back portion of the shirt is eliminated, as well as the sleeves, thus forming 10 an exceedingly cool arrangement for the warm season. A garment constructed in this manner has all of the appearances of a complete shirt and coat and as the shirt portion of the garment is provided with a 15 skirt, the riding up thereof is eliminated and no annoyance or inconvenience is caused to the wearer thereof.

With a garment of this construction an ordinary belt 26 may be utilized for holding 20 up the trousers or suspenders E or both may be used simultaneously. In case suspenders are to be used for supporting the trousers D, each of the sections 13 and 14 of the front portion 10 are provided with 25 slits 27 so that the forward bands 28 of the pair of suspenders E may be inserted therethrough. In order to prevent the tearing of the shirt sections at this point, a U-shaped 30 guide 29 has its terminals stitched as at 35 on each side of the slit and this member forms a guide for the suspenders as well as the means for the prevention of the tearing of the slit. The stitching 20 for the rear skirt or tail portion 11 of the shirt terminates 40 at the central portion thereof as indicated by the numeral 30', and this forms a means for permitting the rear band 31 of the suspenders E to be inserted therethrough for engaging the button carried by the

45 trousers.

If so desired cuff portions, (not shown) may be detachably or integrally connected to the terminals of the coat sleeve in such a manner as to protrude slightly beyond the 45 coat sleeve.

When it is desired to wear the improved garment, the front sections 13 and 14 are disconnected and the arms are inserted 50 through the sleeves of the coat. The coat tail is then raised and the rear portion 11 of the skirt is inserted in place after which the front sections 13 and 14 are buttoned together. The collar and necktie are then placed on the collar band in the usual man-

ner and the garment presents the appearance of a complete shirt and coat.

Changes in detail may be made without departing from the spirit or scope of this invention; but,

I claim:

1. A garment comprising a coat and a shirt section, the shirt section including a front portion a neck portion and a rear skirt portion, and means connecting the shirt portion to the coat section, said skirt portion extending from a point below the coat section to a point above the waist line thereof and extending forwardly from the rear portion of the coat section to the front shirt portion.

2. A garment comprising a coat and a shirt section, the shirt section including a front portion, a neck portion, and a rear skirt portion, means connecting the rear skirt portion adjacent its upper edge to the coat section intermediate its ends, and means connecting the rear upper edges of the front portion and the lower inner edges of the neck portion to the coat section.

3. A garment comprising a coat and a shirt section, the shirt section including a front portion, a neck portion, and a rear skirt portion, the front portion including a pair of independent sections, each consisting of a bosom and a skirt portion, means for detachably connecting the meeting portions of the front shirt sections together, the neck portion and front portion being integrally connected together, the rear skirt portion having its upper edge secured to the coat section above the waist line thereof, and stitching connecting the neck portion, the rear edges of the sections of the front shirt portion, and the upper edge of the rear shirt portion to the coat section.

4. A garment comprising a coat and a shirt section, the shirt section including a front, a neck, and a rear tail portion, stitching connecting the upper edge of the rear tail portion to the coat portion intermediate its ends, the stitching ending short of the central portion of the rear tail portion to form a suspender receiving opening between the coat and rear tail portion, the front shirt portion having a pair of spaced slots 105 therein for receiving suspender bands.

WILLIAM M. SPILMAN.
